ments 10 and 11 of the radiator at the top thereof and is mounted on the upstanding shaft 20 of the motor C. Preferably the blades 21 of the fan are inclined so that they will draw air from the atmosphere downwardly through the circular air inlet opening 22 in the top of the casing D and will force or push such air laterally between the fins 16 of the core elements 10 and 11 and outwardly through the outlet openings 23 and 24 in opposite ends of the casing D.

To facilitate the flow of air from the inlet 22 to the outlets 23 and 24, I have provided a deflector 25 that is substantially frusto-conical in configuration and that encircles the motor C for the fan B. Preferably this deflector 25 is an integral raised portion of the bottom 26 of the casing and is provided at its upper end with an inturned flange 27 that serves as a support for the motor C. As shown, suitable attaching bolts 28 for the motor extend from the upper end thereof through openings 29 in the inturned flange 27 and are held in place by nuts 30 on said bolts. To cushion the assembly and to deaden noise and vibration, there are resilient pads or grommets 31 sleeved on the bolts 28 and having portions above and below the inturned flange 27.

The motor C is of conventional design and extends downwardly through an opening 32 in the bottom 26 of the casing D. Such motor may be electrically connected by any suitable means such as the electric conductors 33 to the usual electric circuit of the motor vehicle and may be under the control of any suitable electric switch (not shown) in said circuit.

To protect and conceal the downwardly projecting lower end of the motor C, there is a substantially cup-shaped shield D' that opens upwardly toward and is secured to the bottom 26 of the casing D. In the present instance, attachment between the shield D' and casing D is accomplished by bolts 34 and nuts 35, and the bolts 34 extend downwardly through the bottom 26 of the casing and through the lateral attaching flange 36 of the shield for attachment to the floor E of the motor vehicle. Thus, the bolts 34 not only serve as a part of the attaching means for the shield D' but also as a mounting for the heater upon the floor E of the motor vehicle.

The casing D is preferably formed of sheet metal and comprises an upper section 37 and a lower section 38. The upper section 37 forms the top and upright walls of the casing, while the lower section 38 forms the bottom of the casing and the combined deflector and motor support 25. Preferably the top of the casing 39 is provided around the central inlet opening 22 with an upstanding annular flange 40 of inverted L-cross section to which a suitable protecting screen 41 for the fan B is secured, while the bottom 26 of the casing has an upstanding marginal flange 42 that serves as an attaching member for the lower section 38 and is adapted to be fastened by suitable screws 44 to the upright walls of the upper section 37.

As shown, some of the fins 16 of the radiator are disposed in the air outlet openings 23 and 24 in the casing and thus serve as grilles through which the heated air may be discharged from the casing.

To cushion the heater and deaden noise, there are resilient bushings or grommets 45 sleeved on the L-shaped tubes 17 and 18 and sealing the openings 46 in the bottom 26 of the casing through which the tubes 17 and 18 extend, and

having lateral flanges 47 beneath the casing for engagement with the floor E of the vehicle. Also a resilient ring or grommet 48 is sleeved on the shield D' underneath the casing for engagement with the floor E of the vehicle. If desired, resilient pads 49 and 50, respectively, may be secured to the top and bottom of the core sections 10 and 11 for engagement with the top 39 and bottom 26 of the casing.

10 When the heater is installed in the body of a motor vehicle, it is preferably mounted on the floor E beneath the front seat F of the vehicle and is connected by suitable hose 51 and 52, respectively, to the water circulating system of the 15 vehicle engine G. If desired, a valve 53 may be included in the hose 51 at the point where it is connected to the head 54 of the engine to control the flow of hot water from the engine through said hose 51 to the heater. The other 20 hose 52 may be connected by the nipple 55 to the radiator hose 56. Preferably the nipple 55 includes cooperating clamping portions 57 and 58, respectively, for gripping a wall of the radiator hose 56, and an adjusting nut 59 threadedly 25 engaging the nipple stem 60 upon which the hose 52 is mounted.

Thus, from the foregoing, it will be apparent that I have provided a heater that is mounted out of the way beneath the front seat of the 30 vehicle. Inasmuch as the air inlet opening 22 is in the top of the heater casing beneath the seat, and the air outlet openings 23 and 24 are in opposite ends of the casing, a proper circulation of air within the vehicle body is assured. 35 In fact, the heater constitutes a register from which the heated air is discharged to the front and rear of the seat F. Actually such heated air passes over the floor E in relatively close proximity thereto and thus serves effectively to 40 heat both the front and rear portions of the vehicle.

In the summer time or during warm weather the valve 53 may be closed so that the supply of hot water from the engine G to the heater 45 will be cut off. As a result, the operation of the fan B will then cause a circulation of air for cooling purposes to the front and rear portions of the motor vehicle.

What I claim as my invention is:

50 1. A heater structure for use between the floor and front seat of a motor vehicle, comprising a casing adapted to be mounted upon the floor beneath the front seat of a motor vehicle, said casing having substantially horizontal top and bottom walls and upright end walls, the top wall being provided at approximately the center thereof with an inlet opening for air, the end walls having outlet openings through which air may be discharged to points in front and in rear of 55 said seat, a fan within said casing beneath the inlet opening for circulating air from the inlet opening through the outlet openings, a motor for driving the fan, the bottom wall of said casing having a raised substantially frusto-conical portion 60 encircling and forming an enclosure for a part of the motor, said frusto-conical portion being beneath the fan in the path of air from the inlet opening for deflecting such air toward the outlet openings, and means suspending the motor 65 from said frusto-conical deflector.

70 2. A heater structure for use between the floor and front seat of a motor vehicle, comprising a casing adapted to be mounted upon the floor beneath the front seat of a motor vehicle, said 75 casing having substantially horizontal top and

bottom walls and upright end walls, the top wall being provided at approximately the center thereof with an inlet opening for air, the end walls having outlet openings through which air may be discharged to points in front and in rear of said seat, a fan within said casing beneath the inlet opening for circulating air from the inlet opening through the outlet openings, a motor for driving the fan, an enclosure for the motor rising from the bottom wall of the casing in the path of air from the inlet opening, and having means for deflecting such air toward said outlet openings, and means supporting the motor from said enclosure.

3. A heater structure for use between the floor and front seat of a motor vehicle, comprising a casing adapted to be mounted upon the floor beneath the front seat of a motor vehicle, said casing having substantially horizontal top and bottom walls and upright end walls, the top wall being provided at approximately the center thereof with an inlet opening for air, the end walls having outlet openings through which air may be discharged to points in front and in rear of said seat, a fan within said casing beneath the inlet opening for circulating air from the inlet opening through the outlet openings, a motor for driving the fan, an enclosure for the motor rising from the bottom wall of the casing, and means supporting the motor from said enclosure.

4. A heater structure for use between the floor and front seat of a motor vehicle, comprising a casing adapted to be mounted upon the floor beneath the front seat of a motor vehicle, said casing having substantially horizontal top and bottom walls and upright end walls, the top wall being provided at approximately the center thereof with an inlet opening for air, the end walls having outlet openings through which air may be discharged to points in front and in rear of said seat, a fan within said casing beneath the inlet opening for circulating air from the inlet opening through the outlet openings, a motor for driving the fan, an enclosure for the motor between the bottom wall of the casing and the fan therein having means for deflecting toward the outlet openings air from the inlet opening, and means supporting the motor from said enclosure.

5. A heater structure for use between the floor and front seat of a motor vehicle, comprising a casing adapted to be mounted upon the floor beneath the front seat of a motor vehicle, said casing having substantially horizontal top and bottom walls and upright end walls, the top wall being provided at approximately the center thereof with an inlet opening for air, the end walls having outlet openings through which air may be discharged to points in front and in rear of said seat, a fan within said casing beneath the inlet opening for circulating air from the inlet opening through the outlet openings, a motor for driving the fan, an enclosure for the motor between the bottom wall of the casing and the fan therein, and means supporting the motor from said enclosure.

6. A heater structure for use between the floor and front seat of a motor vehicle, comprising a casing adapted to be mounted upon the floor beneath the front seat of a motor vehicle, said casing having substantially horizontal top and bottom walls and upright end walls, the top wall being provided at approximately the center thereof with an inlet opening for air, the end walls having outlet openings through which air may be discharged to points in front and in rear of said

seat, a fan within said casing beneath the inlet opening for circulating air from the inlet opening through the outlet openings, a motor for driving the fan, a sectional enclosure for the motor, one section rising from the bottom wall of the casing in the path of air from the inlet opening and having means for deflecting such air toward the outlet openings, the other section depending from the bottom wall of the casing, means supporting the motor from the first mentioned section, and means securing the second section to the bottom of the casing and adapted to secure the latter to the floor of the vehicle.

7. A heater structure for use between the floor and front seat of a motor vehicle, comprising a casing adapted to be mounted upon the floor beneath the front seat of a motor vehicle, said casing having substantially horizontal top and bottom walls and upright end walls, the top wall being provided at approximately the center thereof with an inlet opening for air, the end walls having outlet openings through which air may be discharged to points in front and in rear of said seat, a fan within said casing beneath the inlet opening for circulating air from the inlet opening through the outlet openings, a motor for driving the fan, a sectional enclosure for the motor, one section rising from the bottom wall of the casing, the other section depending from the bottom wall of the casing, means supporting the motor from one of said sections, and means securing the other of said sections to the bottom wall of the casing and having means for securing the latter to the floor of the vehicle.

8. A heater structure for use between the floor and front seat of a motor vehicle, comprising a sectional casing adapted to be mounted upon the floor beneath the front seat of a motor vehicle, said casing having substantially horizontal top and bottom walls and upright end walls, the top wall having an inlet opening for air, the upright end walls having outlet openings through which air may be discharged to points in front and in rear of said seat, a fan within the casing beneath the inlet opening for circulating air from the inlet opening through the outlet openings, a motor for driving the fan, one section of the casing having means forming the top and upright walls of the casing, the other section having means forming the bottom of the casing and having means rising from said bottom in the path of air from the inlet opening to deflect air from the inlet opening toward the outlet openings, and means supporting the motor from said air deflecting means.

9. A heater structure for use between the floor and front seat of a motor vehicle, comprising a sectional casing adapted to be mounted upon the floor beneath the front seat of a motor vehicle, said casing having substantially horizontal top and bottom walls and upright end walls, the top wall having an inlet opening for air, the upright end walls having outlet openings through which air may be discharged to points in front and in rear of said seat, a fan within the casing beneath the inlet opening for circulating air from the inlet opening through the outlet openings, a motor for driving the fan, one section of the casing having means forming the top and upright walls of the casing, the other section having means forming the bottom of the casing and having means rising from said bottom and forming an enclosure for the motor, and means suspending the motor from said enclosure.

10. A heater structure for use between the floor

and front seat of a motor vehicle, comprising a radiator and fan, and a common casing for said radiator and fan having two sections, one section forming the top and upright walls of the casing, the other section forming the bottom of the casing and having a portion serving as a deflector for air and as a support for a motor for said fan.

11. A heater structure for use between the floor and front seat of a motor vehicle, comprising a heat exchange element, a fan for circulating air against said element to be heated, a motor for said fan, a deflector for the circulated air encircling the motor, means suspending the motor from the deflector, and a common casing for the heat exchange element, fan and deflector and including a detachable cup-shaped member cooperating with the deflector to form a housing for the motor.

12. A heater structure for use between the floor and front seat of a motor vehicle, comprising a heat exchange element, a fan for circulating air against said element, a motor for said fan, a

deflector for the circulated air encircling the motor, means suspending the motor from the deflector, a casing for said heat exchange element, fan and deflector, and a shield for the motor attached to the casing and cooperating with the deflector to form a housing for the motor, a part of said shield attaching means being operable to mount the whole heater structure upon the floor of a motor vehicle.

13. A heater structure for use between the floor and front seat of a motor vehicle, comprising a casing adapted to be mounted beneath the front seat of a motor vehicle, said casing being provided with air inlet and outlet openings, a fan within said casing for circulating air from the inlet opening to the outlet openings, a motor for driving said fan, a shield for said motor, and a single means for securing the shield to the casing and for securing the latter to a floor of a motor vehicle.

LEWIS W. WELCH.
